UNITED STATES PATENT OFFICE.

GEORGE WILLIAM MASCORD, OF LONDON, ENGLAND.

PRINTING-MACHINE.

No. 830,448.

Specification of Letters Patent.

Patented Sept. 4, 1906.

Application filed November 7, 1903. Serial No. 180,258.

To all whom it may concern:

Be it known that I, GEORGE WILLIAM MASCORD, a subject of the King of Great Britain and Ireland, residing at 5 The Crescent, Church Road, Barnes, London, England, have invented certain new and useful Improvements in and Relating to Printing, of which the following is a specification.

This invention relates to printing-machines, and has special reference to printing-machines of the rotary type wherein an endless web or roll of paper or other material is operated upon.

According to the invention water or spirituous color may be sprayed directly upon the web or sheet in its course through the machine before the first impressional printing, after such printing, or before and during folding, so that thus either a "ground" or "flatting" tint or tints may be given to the plain web or sheets or impressed or printed part or parts, as the case may be. By such means various color effects may be procured very conveniently and inexpensively.

In carrying the invention into effect spraying apparatus is used substantially the same as that provided, as described in the specification filed on application by me of even date, Serial No. 180,259. Other spraying devices and apparatus may be employed.

The invention is illustrated in the accompanying drawings, in which—

Figure 1 shows a diagrammatic elevation of a rotary-printing machine with means incorporated upon it for tinting or coloring the web by direct spraying upon it of color or ink. Figs. 2 and 3 are detailed end elevation and side elevation, respectively, of the spraying devices employed, as illustrated in Fig. 1, with means for cutting off the spray as required in the tinting or coloring of the web. Figs. 4 and 5 show detailed end elevation and side elevation, respectively, of means for giving a lateral movement to the spraying devices employed, as illustrated in the arrangement illustrated in Fig. 1. Figs. 2^a and 4^a are diagrammatic views showing the fundamental effects that are produced, respectively, by cutting off the spray, as illustrated in Figs. 2 and 3, and by the lateral movement of the spraying devices, as illustrated in Figs. 4 and 5.

It will be understood that for multicolor printing a number of spraying devices may be arranged one above the other for spraying color direct upon the web and so as to render

it possible to associate or blend two colors together to produce a particular secondary or resultant hue or tint, if required, while the means employed for adjustment may be so arranged as to render the respective parts easy of adjustment to vary the tint or to intermittently stop the spraying, as may be required in the working of the machine. Similarly the spraying devices may be arranged in horizontal series or they may be provided so as to be capable of adjustment horizontally or vertically upon a pivotal center.

Means provided for spraying color upon the web are illustrated in Figs. 1 and 5 of the accompanying drawings. A shield or shields 10 of a shape and of a number corresponding to the spraying devices *h* employed in any particular case may be provided in such relation thereto as to be capable of being intermittently brought into position to intercept the spray. The reciprocating or vibrating movement of these shields may be effected automatically from any continuously-rotating shaft on the press, such as 11, and by such means connecting rods or links 12 and levers 13, which may be so provided as to move the shield or shields 10 in front of the spraying device or devices *h* to intercept the spray as determined according to the particular work to be done. Such an arrangement is particularly serviceable in spraying color direct onto the web where a particular tint or tints may be deposited on the web in any particular part of a page or on any particular page or pages, as may be required. The movement of the shield or shields 10 may be effected quickly, so that the spray may be cut off instantly by such means as a cam 14, Fig. 4, so that the cessation of spray shall only be momentary. The shields 10 are advantageously mounted upon a rod 15, extending across the machine, and are made in sections of standard width by which the total effective width of the shields may be reduced or increased, as required in particular cases. The respective sections constituting the shield may advantageously be provided with their circumference concentric with the rod upon which they are mounted, and they may be carried by means of a ledge 17, reaching across the machine, which ledge is integral with an arm 18, capable of sliding upon or of being securely fixed in any position upon the rod 15. The shield 10 may be provided of separate sections corresponding to the width of the spraying devices, with their peripheral

110

edges in a straight line or the line thereof may be substantially V-shaped or oblique or otherwise disposed so that in the movement of the shield any desired effect may be produced upon the web. The lateral movement of the shields may be effected by means substantially the same as that employed for effecting the lateral movement of the spraying devices, as hereinafter described. I advantageously effect the vibratory movement of the shields from one of the gears of the press—for example, from one of the intermediate gears 19, Fig. 1, between proximate printing-couples—*e. g.*, A B.

15 As illustrated in Figs. 4 and 5, a lateral movement may be communicated to the sprayers *h* or to the rod *j*, upon which they are mounted, by means the same as illustrated in Figs. 10 to 12 of the drawings accompanying the companion application of even date, which permits of the cam 4 being adjusted into any particular angular position as required to give the lateral movement to the spraying devices *h* at the proper time.

20 It also permits of cams of various shape being employed to give movements according to the particular effects that are to be produced, or instead the toothed gear-wheel 19 may be slotted and may carry the extremity 25 of the rod 12, by which thus a positive movement may be given to the rod *j* and the spraying devices *h* direct from the gear-wheel 19. A number of spraying devices in horizontal or vertical series may be provided before, 30 after, or between the printing-couples, and by their means water or spirituous color may be sprayed upon the web 20 according to any particular ground that may be required. For example, when it is required to employ one 35 side of the web as the cover or outside sheet of a printed and folded product a set of spraying devices will be provided to continuously apply color on the web at that part, or if only one side of the folded cover-sheet requires 40 tinting a shield may be employed to intercept the spray periodically, so as to only tint the part of the web required. Fig. 2^a shows the effect of thus intercepting the spray completely across the web at equal intervals of 45 time by such mechanism as that illustrated in Figs. 2 and 3, or, again, the edge of the web employed as the cover or the whole web itself may be tinted with various colors to produce a wave effect, Fig. 4^a, in which case 50 a number of spraying devices *h*, corresponding to the number of colors used, may be arranged in horizontal series over that part of the web to which a lateral movement may be communicated by such mechanism as that 55 illustrated in Figs. 4 and 5 at a rate corresponding to the speed of the web, or, again, the web or part of the web may be com-

pletely covered with one tint by one set of sprayers, while a part of the web may be covered with another tint to cover the first, so that advertisements or other matter might be attractively and prominently brought out. It will thus be understood that innumerable effects can be produced by the provision of sprayers for the lateral movement, as hereinbefore described, and by the employment of shields for the periodic interception of the spray either in a circular or in a lateral movement of the shields.

What I claim as my invention, and desire to secure by Letters Patent, is—

1. In a printing-press, the combination with a rotary printing-couple and means for feeding a web to be printed thereto, of means for spraying color upon said web, substantially as described.

2. In a printing-press, the combination with a rotary printing-couple and means for feeding a web to be printed thereto, of means for spraying coloring material to said web, and means for varying the action of said spraying device, substantially as described.

3. In a printing-press, the combination with a rotary printing-couple and means for feeding a web thereto, of devices for spraying coloring material to said web and means for interrupting the operation of said spraying devices, substantially as described.

4. In a printing-press, the combination with a rotary printing-couple and means for feeding a web thereto, of a spraying device for spraying liquid coloring material upon the web, and means for moving said spraying device transversely of the web, substantially as described.

5. In a printing-press, the combination with a rotary printing-couple and means for feeding a web thereto, of a spraying device for spraying liquid material upon the web, an intercepting device and means for inserting it between the web and spraying device, and removing it at suitable intervals, substantially as described.

6. In a printing-press the combination with a rotary printing-couple and means for feeding a web thereto, of a spraying device for spraying liquid material upon the web, and an intercepting device for insertion between the web and spraying device consisting of shield units corresponding to column and sheet widths, substantially as described.

In testimony whereof I have signed my name to this specification in the presence of two subscribing witnesses.

GEORGE WILLIAM MASCORD.
